UNITED STATES PATENT OFFICE.

THOMAS C. BENBOW, OF ABSAROKEE, MONTANA, ASSIGNOR OF ONE-HALF TO GEORGE W. PIERSON, OF RED LODGE, MONTANA, SEVER T. SIMONSON, OF ABSAROKEE, MONTANA, AND PATRICK LAVELLE, OF COLUMBUS, MONTANA.

AIR-SHIP.

SPECIFICATION forming part of Letters Patent No. 774,643, dated November 8, 1904.

Application filed March 27, 1902. Serial No. 100,238. (No model.)

To all whom it may concern:

Be it known that I, THOMAS C. BENBOW, a citizen of the United States, residing at Absarokee, in the county of Carbon and State of 5 Montana, have made certain new and useful Improvements in Air-Ships, of which the following is a specification.

My invention is an improvement in air-ships, and especially in that class of such ships 10 which employ gas-bags forming supports for the car; and the invention relates particularly to means for propelling the car in either direction, for causing the same to descend, and for aiding in the ascent of the ship; and the invention 15 consists in certain novel constructions and combinations of parts, as will be hereinafter described and claimed.

In the drawings, Figure 1 is a side view, and 20 Fig. 2 an end view, of an air-ship embodying my invention. Fig. 3 is a vertical longitudinal section of the car, showing the means for driving the propelling-shafts and for controlling the adjustment thereof to secure the desired movements of the car. Fig. 4 is a detail 25 tail side view illustrating the means for shifting the guide or cam which opens and closes the wings of the propeller-wheels. Fig. 5 is an enlarged section illustrating the devices for driving and opening and closing the wings of 30 the propelling-wheel. Fig. 6 is a detail sectional view on about line 6 6 of Fig. 4. Fig. 7 is a cross-sectional view; and Fig. 8 is a diagrammatic side view of one of the propeller-wheels, illustrating the means for bracing the 35 wings thereof.

As best shown in Figs. 1 and 2, the car A is suspended from a longitudinal bar B by means of the cables B', and said bar B is suspended from the top frame D by means of the cables 40 D', and the bridles E' of the gas-bags E are connected with the frame D, as shown in Fig. 2. It will be noticed that I employ two gas-bags E and connect their bridles E' independently with the top frame D and at the opposite 45 sides thereof. These bags E are independent, and the purpose of employing two is in case one should become punctured in any manner

it would when deflated drop down beneath the other bag and be sustained thereby during the descent of the ship. Also by employing a 50 top frame and connecting the gas-bags with the opposite sides thereof and suspending the car beneath said top frame at a considerable distance therefrom I provide space for the deflated bag without interfering with the operation of the propeller-wheels, so that the said 55 wheels will be capable of operation if one of the bags should be thrown out of action. In the operation referred to it will readily be seen that if one bag E should become deflated it 60 would drop down and hang between the other gas-bag and the car and the deflated bag and the car would be sustained by the other gas-bag or be controlled in its descent thereby, so the ship will gradually sink to the ground. 65 During such operation the propeller-wheels presently described may be employed to assist the gas-bag in controlling the descent of the car and for steering the ship, as will be understood from the following description.

The car A is provided on its under side with a runner A' and springs A² between the said runner and the car, the purpose of such construction being to ease the shock of the car in landing. The car is provided with propeller-wheels arranged in pairs, any suitable 75 number of pairs being employed and the wheels of each pair being opposite each other at the opposite sides of the car and operating along the outer side of the car, as will be 80 understood from Figs. 1, 3, and 7. In the construction shown I employ two pairs of wheels, and as the wheels are constructed and supported alike the description of one will answer for all. The wheel-shafts F are 85 journaled in suitable bearings in the car, such bearings being preferably afforded by the short tubular shafts G, which carry the cam-wheels G' and sprocket-wheels G² and are journaled at G³ in the car, as shown in Fig. 5. 90 The propeller-wheels H are fixed to the shafts F, and such shafts are provided with sprocket-wheels F', geared by sprocket-chains F² with an engine or motor I, which latter may be of

any desired form. It will be noticed that the chains F^2 connecting the motor with the front and rear shafts F are so arranged as to drive the said shafts in the same direction. The 5 The hollow shafts G are provided with grooved cam-wheels G' or other suitable devices by which to effect the opening and closing of the wings of the wheel H as the latter is revolved, and the said shafts G are preferably adjustable in a rotary direction in order to set the cams to open and close the wheel-wings at different points in the revolution of the wheel. This is preferably effected by means 10 of belts g , which connect the sprocket-wheels G^2 on the same side of the car with the sprocket-wheel J , having an indicator J' registering along a dial K . The sprocket-wheel J turns loosely on a stub-shaft J^2 , having a toothed head or pinion J^3 . The crank L has 15 a handle L' and is fixed to the sprocket J , so it can be operated to turn the same. This crank L has a sliding pin L^2 , which is spring-actuated into engagement with the toothed head J^3 of the stub-shaft and operates when 20 engaged with the said head to lock the sprocket in any position to which it may be adjusted. This construction enables me to quickly adjust the sprocket-wheel to position to adjust the wheels H to open in such 25 position as to cause the ship to move forward or back or up or down, as may be desired, and by making the shifting devices on the opposite sides of the car independent the wings of the wheels on one side may be adjusted 30 relatively to those on the other side in such manner as to facilitate the turning of the ship or the steering thereof in any direction. 35

The wheels H comprise the central disk or hub H' and the wings M supported thereby. 40 I show each wheel as provided with six wings; but manifestly the number of wings may be increased or decreased, as desired. Each wing comprises a frame and a covering M' , which may be of silk or other suitable fabric 45 or material, and the frame includes an outer spoke M^2 , fixed at its inner end at M^3 to the hub H' and inclining thence laterally away from the car toward its outer end. This outer spoke is fixed and maintains its position in all 50 adjustments of the wing of the wheel. The inner spoke N of the wing is pivoted at N' in connection with the hub of the wheel and preferably in a bracket N^2 , secured to the inner side of said hub so the outer arm of the 55 spoke N may fold toward and from the fixed spoke M^2 . The spoke N has an extension N^3 inwardly beyond its pivot N' , such extension being engaged by the cam-guide of the shifting device and preferably by fitting the existing 60 tremity N^3 of such spoke in a cam-groove g' , formed in the periphery of the cam G' . This cam is waved from side to side, so that it alter-

nately opens and closes the wings M of the wheels, the upper wings of the wheels in Fig. 7 being shown open or extended and the 65 lower wings collapsed or closed. The silk M' can be secured to the spokes in any desired manner, and it may be desirable in some instances to employ a bracing-rib M^4 , provided between the inner and outer spokes, as indicated in Fig. 7. In Fig. 8 I show brace-rods O extending from each wing forwardly and uniting with the hub. These rods O , it will be noticed, brace the wings in both directions and increase the stability of the wheels. 70 75

If in operation the wheels H are revolved in the direction indicated by the arrows in Fig. 1 and the wings of said wheels be arranged to open when below the shafts F , it will be noticed the ship will be caused to move forward. To reverse the direction of the ship, the hollow shafts G may be given a half-revolution, which will cause the wings to open above the shafts and move the ship rearwardly. To cause the ship to ascend or descend, the shafts G should be given a quarter-turn in one direction or the other, while to quickly steer or turn the ship in one direction or the other the opposite shafts G may be adjusted relatively to cause the opposite 85 wings to open at different points. It will be noticed that by properly marking the dial K it will indicate at a glance the extent to which the sprocket J should be turned to properly adjust the wings of the wheels to operate in 90 the manner desired. 95

Having thus described my invention, what I claim as new, and desire to secure by Letters Patent, is—

In an air-ship the combination with the car, 100 of the operating-wheels provided with collapsible wings having inner and outer spokes, and a suitable web between the same, one of said spokes being foldable whereby to collapse its wings and provided at its inner end 105 with an extension for engagement with the shifting devices, the shaft to which the wheel is secured, the hollow shaft having a cam-wheel engaged by the inner extension of the folding spoke, a sprocket-wheel on said hollow shaft, a sprocket-wheel on the wheel-shaft, the motor, connections between said motor and the sprocket-wheel on the wheel-shaft, the indicating-dial, the sprocket-wheel having a hand registering along said dial, means 110 whereby said sprocket-wheel may be turned and may be locked in any desired adjustment, and a chain connecting such sprocket-wheel with the sprocket-wheel of the hollow shaft, substantially as and for the purposes set forth. 115 120
